[57] **ABSTRACT**

Brush attachment for optional use with a mop frame of the type having a pair of pivoted and lockable wings engagable in opposed pockets of a mop when in planar relationship and swingable to non-planar relationship to permit the wings to be disengaged with the pockets. It is characterized by an elongated brush having a U-shaped frame overlying the mop frame, abutments engaging the forward legs of the wings, and a cam locking device engaging one of the rear legs of the wings. The cam locking device is so constructed to provide a lock to wings which vary somewhat in width thereof.

5 Claims, 6 Drawing Figures

FIG. 1

FIG. 2

COMBINED MOP AND BRUSH ATTACHMENT

BACKGROUND OF THE INVENTION

In the art of mopping floors or the like it has long been the practice to provide a mop with a pair of opposed pockets at the top thereof which receive a pair of foldable and lockable wings of a mop frame, the wings, when in planar position, adapted to secure the mop to the frame, and, when unlocked and moved to non-planar position, adapted to permit removal of the mop from the frame to facilitate cleaning or otherwise reconditioning same. An exemplary form of such construction is disclosed in the U.S. Pat. to Yamen, No. 2,840,840. While mops of this type are well suited for removing dust or other fine debris from the floor, they quickly clog when larger debris is present. To prevent such clogging it is often the practice to first sweep the floor with a brush to remove the larger debris and thence mop the floor with a suitable mop to remove the small debris, thus entailing two separate operations with the attendant consumption of labor and necessity of different equipment.

SUMMARY OF THE INVENTION

The present invention obviates the unnecessary consumption of labor by the provision of a brush attachment for a mop frame of the type referred to which is attached to the front of the mop frame so that the larger debris is swept forwardly so that the mop engages a pre-cleaned floor area and thus minimizes clogging by the larger debris. It thus performs in one operation, the separate brushing and mopping operations sometimes performed by prior practice.

While the broad combination of a brush and mop has been proposed, such devices generally are constructed to be used in combination. The present invention differs therefrom in that the wing type mop frame may be employed separately only for mopping and, when brush sweeping is also desired, a brush in the form of an attachment may be quickly applied to a wing type mop frame.

The principal object of the invention, accordingly, is the provision of a brush attachment for a foldable wing mop frame which may be optionally used with a mop carried by the mop frame.

Another object is the provision of a brush attachment which may be added as an accessory to certain mop frames previously purchased by users.

Another object is the provision of a novel combination of a mop frame of specific type and a brush attachment for same.

A further object is the provision of a brush attachment which may be applied to mop frames of the folding wing type which vary somewhat in the width of the wing legs.

Still further objects, advantages and salient features will become more apparent from the detailed description to follow, the appended claims and the accompanying drawing to now be briefly described.

BRIEF DESCRIPTION OF DRAWING

FIG. 1 is a side elevation of the subject of the invention illustrating a bristle brush attachment affixed to a mop frame;

FIG. 2 is an isometric view of the brush attachment;

FIG. 3 is plan as viewed in the direction of arrow 3, FIG. 1;

FIG. 4 is a section taken on line 4—4, FIG. 3; FIG. 5 is a section taken on line 5—5, FIG. 3; and FIG. 6 is a section taken on line 6—6, FIG. 3.

DETAILED DESCRIPTION OF PREFERRED EMBODIMENTS

Referring now to the drawing, and first to FIGS. 1 and 2, brush 10 comprises an elongated bar 12 to which bristles 14 are secured in any desired manner and a channel shaped bar holder 16 secured to bar 12, such as by screws 18. The forward ends of legs 20 of a U-shaped member 22 are welded to bar holder 16 and a plate 24 is welded to the bight of the U. Plate 24 is apertured to rotatably receive a shaft 25 having a handle 26, the lower end of the shaft having a cam 28 to be subsequently described in more detail. The plate also carries a pair of pins 30 to limit rotational movement of handle 26. A pair of channel shaped abutments 32, 32 are also welded to bar holder 16, the purpose of which will also subsequently appear. The elements so far described comprise the essential structure of the brush attachment for a specific type mop holder to now be described in detail.

Referring now to FIG. 3, mop holder 34 comprised a pair of U-shaped wings 36, 36 which engage within pockets 38, 38 of mop 40. The wings are pivotally secured together midway between their ends so that they may swing between planar relation and non-planar relation for releasing same from the pockets. A grid-like member 42 is welded to one of the wings and is provided with a rod 44 which may be locked to rod 46 which carries a rotatable latch 48, as best shown in FIG. 6. As will be apparent, when latch 48 is rotated counterclockwise (FIG. 6) the two wings are free to pivot to non-planar relationship to permit release thereof from the mop pockets. Grid 42 also has affixed thereto a handle support or bracket 50 which may swivel about the longitudinal and horizontal axis of the wings. Handle 52 is connected to the bracket by a wing nut and screw 54 for swivelling about the wing screw axis. Thus, the handle may be disposed at various angles relative to the floor and at various angles relative to the direction in which the mop and brush are moved across the floor. Thus, the connection of the handle to the mop frame serves the purpose of a universal joint, except that the handle may be clamped to bracket 50 by wing screw 54 to dispose it at an angle relative to the direction of movement of the mop and brush.

In applying the brush to the mop frame, U-shaped member 22 is moved downwardly along the handle and abutments 32 are engaged with the forward legs of the wing members. Cam 28, as best shown in FIG. 5, is aligned with one of the rear legs of the wings and handle 26 is rotated until it abuts a stop pin 30. As will be apparent, this produces a compressive force on the frame and locks same between abutments 32 and cam 28.

Cam 28, as illustrated in FIG. 5, is actually two cams 28, 28' having different eccentricities so that one or the other may be selected for use with mop frames having differing wing widths. Thus, when the handle is disposed in the position of FIG. 2, the cam is unlocked. A 90° movement from this position in one direction or the other then locks the brush to mop frames of variable width. It will be apparent, however, that a single cam may be formed with increasing eccentricity so that during movement through about 90° it will lock to a wide

frame and by continued rotation through about another 90° it will lock to a more narrow frame. It thus becomes apparent that if the cam eccentricity is chosen to lock to the widest mop frame encountered, and also the most narrow encountered, it will be effective to lock to any others intermediate between the range of widths referred to.

What is claimed is:

1. A brush in combination with a mop having a frame of the type having a pair of like outwardly extending U-shaped wings pivotally connected together between ends thereof, the wings, when in planar relationship, adapted to engage within opposed pockets at the top of an elongated mop, and when disposed in non-planar relationship, adapted to permit removal of the mop therefrom, said wings forming generally parallel legs at the front and rear edges thereof, and means for locking said wings in planar relationship, comprising:

    said brush being elongated and of a length coextensive with the length of the mop and having bristles 20 adapted to sweep a floor ahead of the mop, and means for releasably securing said brush to said generally parallel legs.

2. A brush in accordance with claim 1 wherein said generally parallel legs are formed of circular wire or 25 rod and said means for releasably securing said brush thereto comprises open channel abutments secured to the brush adapted to partially surround the front legs of the wings, a U-shaped member secured to said brush adapted to lie above the mop frame and having a bight portion disposed adjacent the rear legs centrally thereof, a rotatable cam carried by the bight portion for releasably engaging at least one of the rear legs of the wings for forcing the front legs into the channel abutments, and a lever for rotating same into and out of en-

5

gagement with a rear leg.

3. A brush for use with a mop having a frame of the type having a pair of like outwardly extending U-shaped wings pivotally connected together between ends thereof, the wings, when in planar relationship, adapted to engage within opposed pockets at the top of an elongated mop, and when disposed in non-planar relationship, adapted to permit removal of the mop therefrom, said wings forming generally parallel legs at the front and rear edges thereof, and means for locking said wings in planar relationship, comprising:

    said brush being elongated and of a length coextensive with the length of the mop and having bristles adapted to sweep a floor ahead of the mop, and means for releasably securing said brush to said generally parallel legs;

    said generally parallel legs being formed of circular wire or rod and said means for releasably securing said brush thereto comprising open channel abutments secured to the brush adapted to partially surround the front legs of the wings, a U-shaped member secured to said brush adapted to lie above the mop frame and having a bight portion disposed adjacent the rear legs centrally thereof, and means carried by said bight portion for releasably engaging at least one of the rear legs of the wings for forcing the front legs into the channel abutment.

4. A brush in accordance with claim 3 wherein the means carried by the bight portion comprises a rotatable cam and a lever for rotating same into and out of engagement with a rear leg.

5. A brush in accordance with claim 4 wherein said cam is so constructed to engage frames having variable distance between the front and rear legs.
